UNITED STATES PATENT OFFICE

NATHAN M. LOWER, OF PITTSBURGH, PENNSYLVANIA, ASSIGNOR, BY MESNE ASSIGNMENTS, TO THE STANDARD STOKER COMPANY INC., OF NEW YORK, N. Y., A CORPORATION OF DELAWARE

LOCOMOTIVE STOKER

Application filed March 13, 1924. Serial No. 699,096.

This invention relates to stokers, and more particularly to stokers for locomotive engines.

- 6 One of the objects of the invention is the provision of new and improved mechanism for delivering fuel onto the distributor plate in front of steam jets for distributing the same within the firebox, the different parts operating in timed relation.
- 10 Another object of the invention is the provision of a new and improved pusher or plunger mechanism for pushing or forcing the elevated fuel onto the distributor plate.

15 Other objects of the invention are the provision of a stoker mechanism that is simple in construction, efficient in operation, cheap to manufacture, and one that is not likely to become broken or get out of order.

20 Other and further objects and advantages 20 of the invention will appear from the following description taken in connection with the accompanying drawings, in which

25 Fig. 1 is a vertical section of a portion of a locomotive and its tender showing the invention in position thereon, with parts in section and parts broken away;

Fig. 2 is a section on line 2—2 of Fig. 1;

30 Fig. 3 is a detail view showing a slightly modified form of the device;

Fig. 4 is a detail view showing a still further modified form of the invention;

35 Fig. 5 is a detail view showing a still further modified form of the device, with parts in section and parts broken away; and

Fig. 6 is a plan view of the same with parts in section and parts broken away.

On the drawings the reference character 10 designates the firebox, 11 the grates, and 12 the back head of a locomotive of any usual or well known construction. The back head is provided with an opening 13 which may be the usual opening through which the hand firing is done, and which may be closed by the doors 14. The floor of the cab is shown at 15 and the deck of the tender is shown at 16.

Since the details of the locomotive and its tender constitute no part of the present invention, the same are not shown on the drawings and will not be further described.

A fuel conduit 17 is located beneath the deck of the tender in the usual manner. The conduit comprises the horizontal section 18 and the upwardly and forwardly extending section 19 which is pivotally connected at its lower end to the forward end of the section 18 by universal joint 20 as is usual in such constructions. The section 19 may have its forward end bent upwardly as at 21, and has attached thereto the distributor plate 22 which is adapted to extend through the door opening 13 of the back head of the locomotive.

A suitable conveyor 23 is mounted in the conduit 17. The conveyor comprises the sections 24, 25 and 26 which are connected together by suitable universal joints. The conveyor is preferably in the form of a screw which is adapted to be rotated by the engine 27 through the shaft 28 and gears 29 in a manner that will presently appear. The conduit section 19 and the sections 25 and 26 of the screw conveyor constitute what may be termed a fuel elevator.

The distributor plate 22 is provided with a series of nozzles or nozzle openings 30 each of which is adapted to be supplied with steam through separate or independent conduits 31 which may be formed in said plate. The conduits are adapted to be supplied with steam from the steam pipe 32 through the branch pipe 33, headers 34 and individual pipes 35. The pipes 35 are each provided with a valve 36 whereby the directional force of the blast from the nozzles 30 may be varied.

A suitable plunger or pusher member 37 is adapted to be reciprocated across the upper end of the fuel conduit 17 for moving the fuel on to the distributor plate in front of the nozzles 30 from whence it is distributed over the grates 11. Suitable guides 38 and 39 are provided for guiding the plunger in its operation. The guides are protected by a cover 40 which may be provided with a lid 41 through which access may be had to the plunger 37.

It is desirable that means be provided for operating the plunger, fuel conveyor and the steam blast in timed relation. Any suitable mechanism may be provided for this purpose.

As shown, the plunger 37 is reciprocated by means of the link 42 which has its upper end pivotally connected to the plunger 37 as at 43. The lower end of the link 42 is bifurcated and is provided with slots 44 which are adapted to engage pintles 45 rigidly secured to each side of the conveyor conduit 17. The link is also provided with a slot 46 which is adapted to engage a pin 47 carried by the 10 wheel 48 which is adapted to be rotated by chain and sprockets from the countershaft 49. The shaft 49 is rotated from the power shaft 50 of the engine 27 through the gears 51 and 52. Suitable means are provided for 15 preventing or minimizing the delivery of fuel during the interval in which the plunger is in position across the upper end of the fuel conduit. In the form of the device selected to illustrate one embodiment of the invention, a 20 system of elliptic gears is employed for operating the conveyor screw substantially intermittently. As shown, an elliptic gear 53 is mounted on the countershaft 49 and is adapted to mesh with the corresponding elliptic 25 gear 54 mounted on shaft 55 on which is secured the bevel gear 56 which is adapted to operate the shaft 28 through the bevel gear 57.

Means are provided for directing a blast from the nozzles 30 across the ledge 58 of the 30 distributor plate 22 during the forward movement of the plunger 37. This may be accomplished by providing the valve 59 in the steam supply or branch pipe 33 with an elongated spring-pressed stem 61 which is adapted to 35 engage a cam 62 on the shaft 49 for opening said valve.

The parts are so constructed and arranged that when the plunger is in the position shown in full lines in Fig. 1 the elliptic gears will be 40 in such position that the conveyor screw will be operating at its maximum speed and the valve 59 will be closed as indicated in this figure. When the plunger is in the dotted line position shown in Fig. 1 the gears will have 45 rotated 180°, the valve 59 will be open, and the conveyor screw will be rotating at its minimum speed.

In the operation of the device the fuel is 50 delivered into the space above the upper end of the conveyor screw and the same is pushed by the plunger 37 onto the ledge 58 of the distributor plate 22 in front of the nozzles 30 from which it is distributed by a blast from said nozzles over the grates of the firebox 55 10. The fire is trimmed by properly manipulating or adjusting the valves 36 in the pipes 35.

The form of the device shown in Fig. 3 differs from that shown in Figs. 1 and 2 in 60 that the slot 63 in the link 420 is curved. The intermediate portion of the slot is on an arc described by the pin 47 in moving from the lower to the upper dotted line position shown in Fig. 3. It will be evident that the 65 plunger 37 will be at rest while the pin is

moving from the lower to the upper dotted line position. During this time the conveyor screw is delivering fuel into the space above the conveyor conduit. When the plunger 37 starts to move it will move quite rapidly and 70 complete its cycle in less time than in the type shown in Figs. 1 and 2.

In Fig. 4 is shown a modified form of plunger. In this form of the device the operating link 64 which corresponds to the 75 link 42 of the device shown in Figs. 1 and 2, is pivotally connected at its upper end as at 65 to a rod 66. The rod 66 extends through an opening 67 in the rear end of the fuel receptacle 68. A pusher foot or bar 69 is 80 pivotally mounted on the forward end of said rod and is provided with a shoulder 70 to limit its pivotal movement rearwardly. The foot may be moved to a position in alignment with the rod 66 or to a position at right 85 angles thereto. When the pusher mechanism is moved forwardly the foot takes the position shown in full lines and pushes the fuel onto the ledge 58 in front of the nozzles 30 in a manner similar to the plunger 37 of Fig. 90 1. When the rod 66 is retracted, however, the foot 69 is free to take the dotted line position shown in Fig. 4 and consequently may be easily withdrawn across the fuel. With this arrangement the conveyor 95 23 or fuel transfer screw may operate continuously and at a constant speed as the pivoted foot will permit the retraction of the pusher member across the fuel that has accumulated above the conveyor 23 during the forward 100 movement of the foot or pusher member 69.

In the form of the device shown in Figs. 5 and 6, the general arrangement of the plunger, elevator, distributor plate, etc., is substantially the same as that previously described. In this form of the device the construction of the plunger has been modified to vary the relative delivery of fuel to the sides of the distributor plate. As shown, the plunger 71 comprises a frame or support 72 110 in which the plunger head 73 is pivoted by means of the vertical pivot 74 passing through the median portion of said head. The head 73 is pivoted between upper and lower parallel walls of the support, and its 115 ends are provided with curved skirts 75 which engage corresponding curved surfaces on the support for preventing the fuel from escaping past the head.

By means of this arrangement the amount 120 of fuel delivered to one side of the firebox may be varied relatively to the other. If, for instance, it is desired to deliver more fuel to the right side of the firebox than to the left, the head 73 is turned as shown in 125 Fig. 6. If more fuel is desired on the left, than on the right the head is turned toward the left. In other words, the inclination of the head will cause a corresponding increase 130 or decrease in the amount of fuel delivered

to one side or the other of the firebox, due to the inclination of the fuel contacting face 73, as will be obvious from an inspection of Fig. 6.

5 Suitable means are provided for adjusting the head. As shown, a lever or handle 76 pivoted as at 77 to the head 73 is employed for this purpose. The handle is provided with a lug or pin 78 which is adapted to engage any one of a series of holes 79 in the quadrant 80 carried by said support. A spring 810 holds the handle 76 depressed for holding the head in adjusted position.

15 Access may be had to the plunger through the door 81. When it is desired to adjust the plunger head 73 the door 81 is opened and the handle 76 raised against the tension of the spring to withdraw the pin 78, after which the handle may be moved to adjust 20 the head to the desired angle.

25 If desired the distributor plate 83 may be provided with enlarged curved wings or ledges for directing the fuel laterally.

30 The operating mechanism including the conveyor 23, link 42, operating wheel 48, conduits 31 and nozzles 30 is substantially the same as that previously described.

35 It is thought from the foregoing taken in connection with the accompanying drawings 40 that the construction and operation of my device will be apparent to those skilled in the art. Various changes in size, shape, proportion and details of construction may be made without departing from the spirit and scope 45 of the appended claims.

I claim as my invention:

1. In combination, a fuel conduit having one end extending upwardly, a distributor plate extending forwardly from the upper 40 end of said conduit, a nozzle between said conduit and the forward end of said plate, means for conveying fuel along said conduit, a plunger and means for moving said plunger for delivering the fuel, elevated through 45 said conduit, onto said plate in front of said nozzle.

50 2. In combination with the back head of a locomotive having an opening therein, a conduit, a distributor plate extending from said conduit into said opening, a conveyor in said conduit, for delivering fuel adjacent to said opening, means for operating said conveyor at variable speeds, a plunger for forcing said fuel onto said plate, mechanism for 55 operating said plunger, said means and mechanism being so constructed and arranged that the speed of said conveyor decreases as said plunger moves forwardly and increases as said plunger moves rearwardly.

60 3. A plunger for transferring fuel comprising a support, a head pivoted to said support and means for adjusting and securing said head in angularly adjusted position relatively to said support.

65 4. In combination, a distributor member,

a plunger for delivering fuel to said member, means for delivering fuel in the path of said plunger and means for adjusting said plunger to vary the delivery of fuel to the sides of said distributor member.

70 5. In combination, a distributor plate, a plunger in the rear of said plate for moving the fuel to the forward portion of said plate, means for delivering fuel in the path of said plunger, and means for causing said plunger to vary the relative amounts of fuel delivered to the two sides of the forward portion of said plate.

75 6. In combination, a fuel conduit having one end extending upwardly, a distributor plate extending forwardly from the upper end of said conduit, a nozzle between said conduit and the forward end of said plate, mechanical means for conveying fuel along said conduit, mechanical means separate and apart from said first named means for advancing the fuel from said conduit on to said plate in front of said nozzle and means for operating said first named mechanical means.

80 7. In combination, a distributor member, mechanical means for delivering fuel to said member, means separate and apart from said first named means for delivering fuel into the path thereof and means for adjusting 85 said mechanical means to vary the delivery of fuel to the sides of said distributor member.

85 8. In combination, a distributor plate, mechanical means rearward of said plate for advancing fuel to the forward portion of said plate, means separate and apart from and for delivering fuel in the path of said mechanical means, and means for adjusting said mechanical means for causing said mechanical means to vary the relative amounts of fuel delivered to the two sides of the forward portion of said plate.

90 9. In a stoker, a distributor member, fuel distributing means for projecting fuel forwardly from said member, means for conveying fuel from a source of supply and delivering the same onto said distributor member outside of the zone of action of said distributing means, and mechanism for moving 95 said fuel into the zone of action of said distributing means whereby the same may be projected forwardly by said distributing means.

100 10. In a stoker, a distributor member, distributor means for projecting fuel forwardly from said member, mechanism for intermittently delivering fuel to said member outside of the zone of action of said means, pusher mechanism for pushing said fuel into the 115 zone of action of said means and means for actuating said pusher mechanism in timed relation to the operation of said first named mechanism.
